OPERATING MECHANISM FOR A WINDOW
AND CASING ASSEMBLY

Clarke C. Curley, Lorain, Ohio

Application January 22, 1947, Serial No. 723,477

1 Claim. (Cl. 268—122)

1

This invention relates to an operating mechanism for a window and casing assembly.

An object of the invention is to provide a window casing comprising an inner section and an outer section, which interlock by tongue and groove guides, the sections being retained in interlocked position by bolts.

Another object of the invention is to provide a window and casing assembly that, made of metal, is fireproof, has a dual glass storm window protection incorporated therein and, provided with screening, makes a highly efficient unit that is adapted for use during all seasons of the year.

Another object of the invention is to provide a mechanical lift for the window that is easy to operate, and the arrangement of the lift providing a burglar-proof unit.

With the above and other objects and advantages in view, the invention consists of the novel details of construction, arrangement and combination of parts more fully hereinafter described, claimed and illustrated in the accompanying drawings in which:

Figure 1 is an elevational view of an embodiment of the device partly broken away to show the crank mechanism of the lift therefor;

Figure 2 is a sectional view on the line 2—2 of Figure 1;

Figure 3 is an enlarged detailed sectional view of the screw arrangement for the lift device;

Figure 4 is a sectional view on the line 4—4 of Figure 2;

Figure 5 is an enlarged detailed view of the roller guide for the linkage for the lift device;

Figure 6 is an elevational view of a modified form of the invention;

Figure 7 is a fragmentary sectional view of the gear arrangement shown in Figure 6;

Figure 8 is an enlarged detailed view of the gear arrangement and

Figure 9 is a modified form of linkage.

Referring more in detail to the drawings, the reference numeral 10 designates in general the window casing assembly which comprises the outer casing section or member 11 and the inner casing section or member 12. The section 11, at its inner edge, is provided with brackets 13 which provide a groove 14 to receive the tongue 15 of the section 12, and a U-shaped bracket 16 secured to the section 11, adjacent the upper and lower ends thereof receives compression screens 17 which are mounted in the bracket 18 and bracket 19 respectively, which are secured to the section 12 inwardly of the outer face thereof.

The section 11, at its outer edges, is placed in position, and the conventional sheathing 20, insulation 21, siding 22 and caulking 23 is employed to finish the interior appearance of the dwelling in which the assembly is positioned. The inner section is sealed by conventional plaster 24 while

the remainder of the dwelling is of conventional structure, as shown at A.

The bracket 19 forms a portion of the box assembly or housing 24 to house the lift mechanism 25, the remainder of the housing 24 being formed on the section 12 as shown at 26.

In Figures 1 and 2, the lift mechanism 25 is shown as comprising opposed disc shaped gears 27 and 28 respectively, which are fixed to the inner ends of shafts 29 and 30 respectively, and these shafts are journalled in brackets 31 fixed to the bracket 19 within the housing 24. The gears 27 and 28 are provided with the row of openings 32 to engage the teeth 33 of the disc gear 34 mounted intermediate of the gears 27 and 28 on the shaft 41, the gear 34 being fixed to the reduced portion 35 of the shaft 41, and a key 36 in the key slot 37 in the portion 35 retains the gear 34 in position by means of the spring washer 38. The portion 35 of the shaft 41 is journalled in the bracket 19 at one end, and bearing washer 39 and cotter key 40 retain the shaft 41 so that the outer flanged end 42 engages the housing 24. A bore 43 in the outer end of the shaft receives the reduced portion 44 of the crank arm 45 and spring pressed balls 46 in the portion 44 engage in the seats 47 in the inner surface of the bore 43 to retain the portion 44 in the bore 43 for the rotation of the gear 34.

Fixed to the outer ends of the shafts 29 and 30 are disc gears 48 having teeth 49, which are similar to gear 34, and the teeth 49 of the gears 48 engage in the openings in the gears 50, which are similar to gears 27 and 28.

The gears 50 are fixed to the lower ends of the jack screws 51, there being one in each side of the section 12, the lower ends of the screws 51 being mounted in the ball bearing supports 52 and the upper ends journalled in the bearing seats 53. Brackets 54 retain the screws 51 in vertical relation to the shafts 29 and 30 within the section 12. Mounted on the screws 51 are the traveling nuts 55 to which is secured the linkage guide arms 56 which travel in the slots 57 during the movement thereof, and also engage the linkage position rollers 58, mounted on the bolt shafts 59 and spaced from the sections 12 by bushings 60 on the bolt shafts 59, which are secured as shown in Figure 5. The arms 56 are provided with a forked end 61 which receives the reduced end 62 of the link 63 and a pin 64 pivots the link 63 in the end 61 of the arm 56. The other end of the link is similarly shaped, having a reduced end 62 which is receivable in the apertured ears 65 of the bracket 66, and a pin 67 pivots the link 63 in ears 65 of the bracket 66.

The assembly thus described is provided at each side of the casing assembly 10, and each bracket 66 is secured to the lower window sash 68 by fasteners 69. Sash 67 has upper and lower

rails 69 to which are secured plates 70 carrying sash glass channels 71 for mounting the inner and outer panes 72 and 73 respectively.

The rails 69 each carry a spring loaded seal assembly which comprises a substantially U-shaped bracket 74 which is secured to the rail 69 by a fastener 75 which also secures the plate 70 to the rail, longitudinal extending opposed baffle plates 76 engaging the bracket 74 which is engaged by the substantially U-shaped sealing means 77 which extends outwardly of the rails to engage the lower rail 78 of the upper sash 79, and the sill portion 80 of the section 11, and this assembly, its use and construction is fully described in my co-pending application for Door Seal Assembly, filed November 30, 1945, Serial No. 632,006, which issued as Patent No. 2,445,315.

The upper sash 79 is also constructed in similar manner to the lower sash, except that the seal assembly is only in the upper rail 80 of the sash.

The upper sash is provided with a sealing or guide stop 81 which is secured to the section 12, and terminates just above the lower edge in a bevelled edge 82, which permits the lower sash to slide past the upper sash in its upward movement, while the guide strip 82 for the lower sash extends upwardly from the lower rail at an inclination to terminate at its upper end adjacent the top of the section 12.

The upper sash is fixed in its closed position, and is provided on the bottom of the lower rail with a drip ledge 83, which prevents water entering the space between the upper rail of the lower sash and the lower rail of the upper sash.

A screen guide channel 84 secured to the section 11 carries the screen 85. The screen is provided with a spring pressed latch 86 mounted in the recess 87 of the screen and receivable in the groove 88 in the guide 84 to retain the screens in raised position.

The window casing assembly is provided with rubber corner pad assemblies 89 to prevent leakage of the casing, and a crank storage bracket 90 may be secured to the section 12, as shown in Figure 6.

The assemblies shown in Figures 6 to 9 inclusive are similar except that gears 48 and 50 are replaced by bevelled gears 91 and 92 respectively, and gears 21, 28 and 33 are replaced by similar shaped gears 93, 94 and 95 respectively, and the shaft 96 for gear 94 is journaled in the ball bearing mounting 97 and a washer 98 welded to the rear of section 12 retains the shaft 96 loosely mounted therein, while a nut and washer assembly 99 retains the gear 94 on the shaft 96 and the crank is connected to the shaft 96 as previously described, with regard to shaft 41.

In Figure 9, the nut 55 carries a stud 100, which engages the elongated slot 101 in the link 102 while the slot 103 in the other end of the link 102 engages the stud 104 in the bracket 105 which is fixed to the sash 67. This is a modified form of linkage, and can be substituted for the linkage previously described.

With the casing assembled as described, providing the closing effect of two flanges, perfect alignment is had at all times.

By turning the crank 45, the linkage pulls the lower sash rearwardly at the upper edge thereof, so that it will slide upwardly in the rear of

the upper sash. The rollers 58 guide the links 63 so that the sash is pulled rearwardly to move upwardly, and pushed forwardly into closed position when lowered. The nut 55 travels on the jack screw 51, raising and lowering the sash as desired, in a simple, easy and efficient manner.

The seal shown included in the sash rails provides an air tight seal at the point of contact, so that the sash, with its double panes of glass, functions as an efficient storm window.

The linkage arrangement prevents opening of the lower sash, making it burglar-proof, and the drip ledge on the upper sash contacting the upper edge of the screen prevents insects from entering at the top of the screen.

From the foregoing description, it is believed that the construction and operation of the assembly will be apparent to those skilled in the art, and it is to be understood that changes in the minor details of construction, arrangement and combination of parts may be resorted to, provided they fall within the spirit of the invention and the scope of the appended claim.

Having thus described the invention, what is claimed as new and desired to be secured by Letters Patent is:

In an operating mechanism for a window frame and upper and lower sash assembly of the sliding type wherein the sash are in vertical alignment with each other, the improvement comprising a pair of vertically disposed jack screws mounted at opposite sides of the assembly, a travelling nut on each jack screw, a pivot on the lower sash and a pivot on the jack screw, guide slots in said frame for the pivot on the travelling nut, rollers mounted on the frame adjacent said guide slot for coaction with said pivot a link connected at its opposite ends to said pivots, a gear on the travelling nut on the lower end of each jack screw, a pair of horizontally disposed shafts provided with gears on both ends thereof, gears on one end of said shaft ends engaging the gear on the jack screw and the gears on the other end simultaneously engaging a gear having an operating handle thereon so that when said handle is rotated to cause the actuation of said gears said travelling nuts will be caused to rotate on said jack screws and through the medium of said links will cause the lower sash to move forwardly of the upper sash and be raised into open position and upon lowering of said lower sash said link will cause said lower sash to be moved into alignment with said upper sash into closed position.

CLARKE C. CURLEY.
